UNITED STATES PATENT OFFICE.

JACOB H. VAN RIPER, OF NEWARK, NEW JERSEY.

TOBACCO-PIPE.

SPECIFICATION forming part of Letters Patent No. 246,249, dated August 23, 1881.

Application filed June 17, 1881. (No model.)

To all whom it may concern:

Be it known that I, JACOB H. VAN RIPER, of Newark, in the county of Essex and State of New Jersey, have invented a new and useful Improvement in Tobacco-Pipes, of which the following is a specification.

The object of this invention is to prevent the entrance of nicotine and essential oils of the tobacco into the mouth of the smoker, and to retain them in the pipe-stem.

The invention consists of a sectional pipe-stem whose two central sections have large bores or chambers for the condensation of the nicotine and essential oils, and are coupled together with a coupling-nut of comparative small bore, provided with reduced terminal central bosses, that serve to retain the condensed oils in the pipe-stem, said nut being inserted into the opposite ends of the central sections, all of which will be hereinafter described.

The drawing represents a vertical sectional elevation of the improved pipe-stem.

In the drawing, A A' represent the two central sections of the pipe-stem, bored or chambered out as much as possible consistent with strength, as shown at a a', respectively, and having each end internally screw-threaded, as shown at b b', respectively.

B represents the screw coupling-nut provided with a central boss, c, on each end, and a small bore, d, extending through its entire length and through said bosses c. A ring or annular rib, f, formed centrally around the nut B enables the operator more readily to turn said nut B. This nut B is screwed into the opposite screw-threaded ends of the sections A A', as shown.

In the chamber a a piece of sponge, g, is preferably inserted, for condensing and holding the oil, &c., from the smoke passing through it.

The lower section, C, of the pipe-stem is inserted into the bottom of the section A', and has a cork envelope, C', upon which the pipe-bowl (not shown) is designed to be fitted, and upon the upper end of said section C is a central tubular extension, h, that forms an annular chamber in the section A', for the retention of

the condensed tobacco-oil, thereby preventing it from flowing into the pipe-bowl.

Into the top of the section A the pipe-section D is inserted, and upon this is fitted the mouth-piece E, as shown.

When in smoking a pipe the stem is held in the usual upright or slightly-inclined position, the major portion of the nicotine and oils will condense in the chamber a, because, being farther away from the pipe-bowl, (not shown,) the said chamber a is cooler than the chamber a', and because the smoke has become cooled in being drawn through the bore d of the coupling-nut B, and the condensed nicotine and oil, condensing in said chamber a, will gradually deposit on the upper end of the nut B, but will be prevented from flowing down through said nut B into the pipe-bowl (not shown) by the upward-projecting boss, c.

At any convenient time the pipe-sections A A' may be uncoupled, and the condensed oil and nicotine be removed.

The sponge g serves as an auxiliary condenser, but may be dispensed with at the option of the smoker.

The coupled sections and nut A A' B may be inverted from their present positions, and the positions of the sections C D reversed, in which case the present lower boss, c, will become the upper one, and serve the same purpose, and the chamber a' serve as a condensing-chamber. Hence it will be seen that in effect this improved pipe-stem is a doubly-chambered reversible stem.

Having thus fully described my invention, I claim as new and desire to secure by Letters Patent—

In combination with the central chambered stem-sections A A', provided with end sections, C D, of the coupling-nut B, provided with end bosses, c, and a small bore, d, extending through its entire length and through the said bosses, substantially as and for the purpose set forth.

JACOB H. VAN RIPER.
